Primary Examiner — Vy N Koenig*(74) Attorney, Agent, or Firm* — Troutman Pepper
Hamilton Sanders LLP; Ryan Schneider; Chris N. Davis(57) **CLAIM**

The ornamental design for a box, as shown and described.

DESCRIPTION

FIG. 1 is a perspective view of our new design for a box;

FIG. 2 is a front view thereof;

FIG. 3 is a right view thereof;

FIG. 4 is a rear view thereof;

FIG. 5 is a left view thereof;

FIG. 6 is a top view thereof; and,

FIG. 7 is a bottom view thereof.

The broken lines are included for the purpose of illustrating a portion of the box that forms no part of the claimed design.

1 Claim, 7 Drawing Sheets(56)
